(57) CLAIM

The ornamental design for a beverage container, as shown and described.

DESCRIPTION

FIG. 1 is a perspective view of a beverage container according to the present invention, with portions shown in broken lines, and therefore, not constituting part of the claimed design;

FIG. 2 is a front view thereof, with the rear view being a mirror image thereof;

FIG. 3 is a right side view thereof, with the left side view being a mirror image thereof;

FIG. 4 is a top view thereof; and,

FIG. 5 is a bottom view thereof.

All broken lines in the above figures are for illustrative purposes only and form no part of the claimed design.
